UNITED STATES PATENT OFFICE.

ALBERT M. YATES, OF TRINIDAD, COLORADO.

HORSESHOE-GAGE.

1,202,348.

Specification of Letters Patent. Patented Oct. 24, 1916.

Application filed March 10, 1916. Serial No. 83,359.

To all whom it may concern:

Be it known that I, ALBERT MATT. YATES, a citizen of the United States, residing at Trinidad, in the county of Las Animas and 5 State of Colorado, have invented a new and useful Horseshoe-Gage, of which the following is a specification.

This invention relates to a gage especially designed for use in measuring the sizes of 10 horse shoes.

Heretofore considerable time has been wasted by horseshoers in repeatedly fitting a shoe to the hoof and it is an object of the present invention to provide a gage which 15 can be fitted to the hoof of a horse prior to the formation of a shoe, after which the shoe can be placed, whenever desired, upon the gage, thus to determine whether or not the shoe has been brought to the proper 20 shape and size.

A further object is to provide a gage the parts of which can be readily adjusted to give the various dimensions of the shoe to be formed and which gage is light and durable in construction and will not readily get 25 out of order.

With the foregoing and other objects in view which will appear as the description proceeds, the invention resides in the combination and arrangement of parts and in the details of construction, hereinafter described and claimed, it being understood that changes in the precise embodiment of the invention herein disclosed can be made 30 within the scope of what is claimed without departing from the spirit of the invention.

In the accompanying drawings the preferred form of the invention has been shown.

In said drawings:—Figure 1 is a bottom 40 plan view of the gage; Fig. 2 is a top plan view thereof; Fig. 3 is a detailed view of one of the plates of the gage; Fig. 4 is a detail view of the other plate of the gage; Fig. 5 is a section on the line A—B of Fig. 45 4; Fig. 6 is a front elevation of one end portion of the actuating lever.

Referring to the figures by characters of reference 1 designates a plate provided at one side with a tongue 2 and at its other 50 side with an elongated arm 3, the outer edges of the tongue and arm being merged into one side edge of the plate 1 so as to form a compound curve which follows the general configuration of one side and a portion of 55 the front of a horse's hoof. Plate 1 has a longitudinal slot 4 disposed parallel with the

straight front edge 5 of the plate, this front edge being extended at an acute angle from the inner edge of the arm 3. Extending from the upper face of the plate 1 are ears 60 6 located at the outer edge of the plate. Graduations are provided upon the bottom of the plate 1 and are extended along the straight edge 5. The other plate 7 of the gage is similar in general outline to the plate 65 1, it being provided with a tongue 8 at one side and with an elongated arm 9 on its other side, the outer edges of the tongue and arm merging into one edge of the plate 7 to form a compound curve of substantially the same 70 shape as one side and a portion of the front of the hoof of a horse. The arm 9 has a slot 10 extending longitudinally therein and another slot 11 is formed longitudinally within the plate 7 and parallel with the front 75 straight edge 12 of the plate and which edge is disposed at an acute angle to the arm 9. A pointer or index 13 is extended from the plate 7 adjacent one end thereof and so as to project at right angles from the straight 80 edge 12. Ears 14 are extended from the edge of the plate 7 and correspond with the ears 6 heretofore referred to.

When the parts engaged are assembled the two plates 1 and 7 are oppositely disposed, the plate 7 extending under the plate 1 and the slots 4 and 11 registering. A screw 15 is slidably mounted in these registering slots and constitutes the fulcrum of a lever 16 arranged under the plate 1 and provided at one end with a finger piece 17 while its other end is pivotally connected to a slide 18. This slide has a stud 19 guided within the slot 10 and a guide finger 20 may be provided upon the inner edge of the 85 slide where it can straddle and travel along the inner edge of the arm 9. A wing nut 21 engages the screw 15 and when tightened will bind the lever 16 and the two plates 90 tightly together so that they will not shift 100 relative to each other. When the parts are thus assembled the index or pointer 13 will lie close to one of the graduations on the plate 1. The pivot screw 22 which connects lever 16 to slide 18 can be placed in any one 105 of a series of openings 23 in the slide 18, thus to provide an adjustable connection between the two parts.

In using the gage the wing nut 21 is loosened thus permitting the various parts 110 of the gage to shift relative to each other. The gage is then placed against the hoof to

which a shoe is to be fitted and the parts are adjusted relative to each other so as to bring the ears 6 and 14 against the opposed sides respectively of the hoof. While the parts are thus held the lever 16 is shifted by pressing against finger piece 17 so as to move the slide 18 longitudinally until the end of the slide is brought below or directly opposite the back end of the hoof. When the parts are thus properly adjusted to the hoof the nut 21 is tightened on the screw 15 and the parts are thus securely bound together. The gage can then be taken to the anvil and during the shaping of the shoe it can be repeatedly fitted to the gage. As soon as the shoe being constructed becomes of the size and shape indicated by the gage, it can be applied and secured to the hoof. Thus the time which has heretofore been wasted in passing back and forth from the animal to the anvil is saved and the cost of producing the shoe is consequently materially reduced.

Having thus described the invention, what is claimed is:

1. A horse shoe gage including opposed slidably connected members having their side edges and one end curved to correspond, substantially, with the configuration of a corresponding portion of a hoof, means outstanding from the members for engaging the sides of a hoof, and means for holding the members against relative movement, and means adjustably mounted on one of the members for determining the length of the shoe to be produced.

2. A horse shoe gage including opposed slidably connected members having their side edges and one end curved to correspond, substantially, with the configuration of a corresponding portion of a hoof, means

outstanding from the members for engaging the sides of a hoof, means for holding said members against relative movement, a slide mounted on one of the members, means movably connected to said last mentioned member for shifting the slide toward one end of the member, said slide constituting means for determining the length of a shoe, and means for holding the slide against movement.

3. A horse shoe gage including opposed members having their outer side edges and one end shaped to conform substantially with the configuration of the sides and one end of the hoof, said members having registering slots extending transversely of the gage, a lever, a slide connected to the lever and shiftable toward one end of one of the members and means extending through the members and the lever for binding them together and preventing independent movement thereof.

4. A horse shoe gage including opposed slidably connected members having their side edges and one end curved to correspond, substantially, with the configuration of a corresponding portion of a hoof, means outstanding from the members for engaging the sides of a hoof, means for holding the members against relative movement, and coöperating means upon the two members for indicating the width of the shoe to be produced.

In testimony that I claim the foregoing as my own, I have hereto affixed my signature in the presence of two witnesses.

A. M. YATES.
